Primary Examiner — Barbara Fox*Assistant Examiner* — Messina L Smith(74) *Attorney, Agent, or Firm* — Stephen E. Zweig(57) **CLAIM**

The ornamental design for a casket, as shown and described.

DESCRIPTION

FIG. 1 is a top front perspective view of a casket showing my new design.

FIG. 2 is a bottom front perspective view thereof.

FIG. 3 is a top plan view thereof.

FIG. 4 is a bottom plan view thereof.

FIG. 5 is a left side elevation view thereof.

FIG. 6 is a right side elevation view thereof.

FIG. 7 is a rear side elevation view thereof; the front side elevation view is a mirror image; and,

FIG. 8 is an exploded view thereof.

The broken line shown in the drawings depict portions of the casket that form no part of the claimed design.

1 Claim, 6 Drawing Sheets---
